UNITED STATES PATENT OFFICE

2,281,493

ELECTRIC CLOCK

Laurens Hammond, Evanston, Ill., assignor to
Hammond Instrument Company, Chicago, Ill.,
a corporation of Delaware

Application February 13, 1931, Serial No. 515,598

13 Claims. (Cl. 58—26)

My invention relates generally to time keeping devices, that is, devices having a timing function such as metronomes, recording meters of various kinds, and in fact, all devices in which constant speed of operation is an essential factor. The invention relates more particularly to improvements in synchronous electric clocks, that is, clocks in which the speed of operation is controlled by the timed impulses of an alternating or pulsating current.

Clocks of this type have come into general use because of their simplicity, quiet operation, durability and high degree of accuracy. The clocks of this type now on the market are for the most part driven by synchronous motors and have the pronounced disadvantage that they stop upon interruption of the supply of alternating current. Several means for overcoming this disadvantage have been proposed but have not come into use because of their commercial impracticability, even though the demand for a clock which will not stop upon interruption of the supply of current is very great. The demand is especially present in many communities where the supply of alternating current is frequently interrupted due to electrical storms, shut-downs in the power generating stations and disconnections in the line necessary for repairs and alterations. Even in communities where the supply of current to the consumer is only very rarely interrupted, the supply of current to the individual clock is frequently interrupted due to accidental disconnection of the plug from the socket through which the clock receives current, blowing of the consumer's fuse, and intentional disconnection of the plug necessitated by changing the location of the clock on the owner's premises.

In one of the attempts to overcome the disadvantage of having the clock stop upon interruption of the supply of current, of which I am aware, it was proposed to add to a self-starting synchronous motor driven clock a complete spring motor driven clock mechanism which served as a stand-by movement to drive the hands of the clock upon interruption of the current, suitable clutch and stop devices being incorporated to cause operation of the clock by the stand-by movement upon interruption of the current supply to the synchronous motor. This attempted solution of the problem presents difficulties in manufacture, greatly increases the cost of the clocks, and is not entirely successful in operation because of the fact that a certain amount of time is "lost" each time the transfer

is made from the synchronous motor drive to the spring motor drive.

Another attempted solution involved the provision of a synchronous motor drive and spring motor drive connected through differential gearing with the hands of the clock, the spring motor drive being held against operation while the synchronous motor was in operation and vice versa. This attempted solution had the same disadvantages as enumerated above except that instead of "losing" time the clock would gain time. The reason for this gaining of time was that it always took a certain amount of time to stop one of the mechanisms and start the other, and hence there was a certain amount of overlap during which interval both mechanisms were operating, thus permitting the differentially movable member of the differential gearing to move twice its normal speed during this interval.

20 In the clock of the present invention there is, strictly speaking, no auxiliary clock movement. Generally, the clock comprises an induction motor geared to wind a spiral clock spring, the driving side of which is geared to a synchronous electric brake which acts in place of the escapement mechanism of an ordinary clock, and prevents the spring from unwinding at greater than a predetermined speed. The rotating part of the synchronous electric brake is also connected to a centrifugal mechanical speed governing mechanism. A pawl and ratchet mechanism prevents the spring from unwinding and rotating the induction motor backward when the current supply is interrupted. The synchronous electric brake is of course ineffective during an interval of current interruption, but during such interval the mechanical centrifugal mechanism is effective to control the speed of operation of the clock. The moving parts of the centrifugal mechanism are 25 continuously rotating so that the transfer of the speed control from the synchronous brake to the centrifugal mechanism is effected without starting or stopping any part, and hence without loss of time.

30 45 It is thus the object of my invention to provide a clock in which the disadvantages of the prior clocks of this type are overcome and which has the advantages above described.

More specifically, the objects of my invention are to provide an improved synchronous electric clock which

- 50 (1) Will operate during extended periods of current interruption;
- (2) Will not require manual rewinding;

(3) Will consume but a small amount of current in operation;

(4) Utilizes a synchronous electric brake to control its speed of operation when current is being supplied to it;

(5) Has a centrifugal continuously rotating mechanical means automatically operable accurately to control the speed of operation of the clock when current is interrupted;

(6) Has centrifugal means running freely when the current is being supplied at the correct frequency, which means, upon a current interruption, are immediately effective to control the speed of the clock mechanism;

(7) Has a spring for rotating the synchronous brake and the centrifugal means;

(8) Has electric induction motor means for winding the spring;

(9) Has dual similar gear trains, one connecting the electric motor means with one end of the spring and the other connecting the opposite end of the spring with the synchronous brake;

(10) Has the similar gears of each of the two trains supported by the same shafts and normally rotatable at the same speed;

(11) Has improved shaft bearings;

(12) Utilizes the centrifugal means as a means to prevent the rotor of the synchronous brake from hunting, and as a means for facilitating easily bringing the rotor of the synchronous brake into synchronism.

Other objects will appear from the following description, reference being had to the accompanying drawings, in which:

Figure 1 is an elevation of the clock face;

Figure 2 is a plan view of the clock;

Figure 3 is a vertical sectional view thereof taken on the line 3—3 of Fig. 4;

Figure 4 is a right side elevation of the operating mechanism of the clock;

Figure 5 is a rear elevation of the mechanism;

Figure 6 is a fragmentary sectional view showing the clock spring and pawl and ratchet mechanism;

Figure 7 is a sectional view taken on the line 7—7 of Fig. 9;

Figure 8 is a sectional view taken on the line 8—8 of Fig. 9 and showing particularly the bearing construction and the means for adjusting the throw of the casing of the centrifugal mechanism;

Figure 9 is an enlarged vertical sectional view taken on the line 9—9 of Fig. 7;

Figure 10 is a developed sectional view showing particularly the gear trains;

Figure 11 is a diagrammatic view of the clock;

Figure 12 is an elevational view of a modified form of mechanical speed governing means;

Figure 13 is a side elevation thereof;

Figure 14 is an elevation of an escapement mechanism;

Figure 15 is a plan view of the escapement mechanism shown in Fig. 14; and

Figures 16, 17 and 18 show the different forms of stator laminations.

General construction

In order that the detailed description of the clock may be more readily understood, the general features of construction and an outline of the operation will be presented first.

The clock comprises three generally similar frame plates 20, 22 and 24. Studs 26, 28, 30 connect plates 20 and 22, and studs 32, 34 and 36

join plates 22 and 24. The clock is of course mounted in a suitable case, not shown, and has a face dial 38, an hour hand 40, minute hand 42, and second hand 44.

5 Referring to the diagram of Fig. 11, the clock comprises an induction motor having an induction rotor 64, which, through the gear train 76, 86, 90, 92, 98, 100, 104, 106, 110 and 112, rotates spring drum 114. The spring 118, the outer end 10 of which is secured to the drum 114, has its inner end secured to the shaft 116, and through gear train 120, 122, 124, 126, 128, 130, 132, 134, 136 and 138, drives shaft 74. The toothed rotor 76 forms a synchronous brake in cooperation with the toothed poles forming part of a suitable magnetic field, and is rigidly secured to the shaft 74. Also secured to the shaft 74 is a mechanical speed governing mechanism, shown in Fig. 11 as comprising weights 200 which are connected to the shaft 74 through a resilient connection.

In this form of mechanical speed governing mechanism, a pawl 178, which cooperates with the ratchet wheel 176 on the spring drum, is operative through arm 182, shaft 186 and arm 226 to raise the raceway 212 when the spring drum 114 begins to rotate clockwise. The hands of the clock are driven by the train of gearing which connects the rotor 76 of the synchronous brake and the shaft 116.

25 In operation, the induction rotor 64, if unimpeded, would rotate at a speed several times as great as the rotor 76 of the synchronous brake, and thus will act to wind the spring 118 and maintain it wound. When the spring is thus wound, a force will be transmitted to the shaft 116 and hence through the train of gearing to the synchronous brake. Assuming that the synchronous brake has been set in motion at synchronous speed (which is accomplished manually), the induction rotor will, through the two trains of gearing and through the spring 18, continue to rotate the synchronous brake and also the centrifugal mechanism which is resiliently connected to the shaft 74 and rotatable therewith.

30 Upon an interruption of the supply of current, the spring 118 will of course tend to rotate the shaft 116 counterclockwise and the spring drum 114 clockwise. The clockwise movement of the spring drum 114 will, however, be arrested in a short time by the pawl 178, so that all of the remaining energy stored up in the spring 118 will be dissipated through driving the train of gearing shown at the right in Fig. 11, and the shaft 74 and all parts rotatable therewith. During the 35 periods of current interruption, the synchronous brake is of course not effective to control the speed of rotation of the shaft 74. During this period, however, the centrifugal mechanism accomplishes this function. When the braking effect of the synchronous rotor is removed upon the interruption of the current, there is a tendency slightly to increase the speed of rotation of the shaft 74. Due to the inertia of the parts, this tendency is not manifest for several seconds, and during this time the pawl 178 will, in the 40 form of centrifugal governing mechanism shown in Fig. 11, have raised the raceway 212 to the position shown in said figure, in which position the weights 200 of the centrifugal mechanism revolve in such close proximity to the lower portion of the raceway that any tendency of the shaft 74 to increase its speed of rotation is pre-

vented by frictional contact of the weights with the lower portion of the raceway 212.

While this centrifugal governing mechanism does not form a perfect time regulating device, it has been found that within the degree of accuracy capable in commercial quantity production, it may be made sufficiently accurate that during a period of half an hour of operation the centrifugal mechanism will maintain the speed of the mechanism so nearly constant that the cumulative error during the half hour's period of operation will not exceed more than a few seconds. Since current interruptions are usually of only a few seconds', or at most a few minutes', duration, it will be apparent that the interruption of the supply of current will normally cause a variation of only a fraction of a second from the correct time.

The induction motor and the synchronous brake

The coil 50, which is adapted to be connected to a suitable source of alternating current by conductors 52 and plug 54, is wound about the inwardly projecting ends of laminations 53, 55, 56, 57, 58 and 59 (Figs. 7, 9, 16, 17 and 18), which are secured to each other by bars 60 and to the frame plate 22 by bolts 62, 63. The laminations 56 and 58 are substantially E-shaped, the ends of the two lower horizontal portions of these laminations being shaped to form field poles for a hard steel rotor 64 of the induction motor, a diametrically opposite pair of these poles being shaded by having a plurality of short-circuited copper bars 66 pressed thereover. The rotor of the induction motor could be made with induction bars, or could be a disc of cold rolled steel, but a hardened steel disc is preferred because of the greater torque which it is capable of developing. The laminations of the unshaded poles are preferably secured against vibration by bolts or rivets 63. The inner laminations 57, 59, of which there are several pairs, have diametrically opposite inwardly projecting portions 57' and 59' which form poles for the rotor 70 of the synchronous brake. These poles are toothed to register with the teeth formed upon the rotor 70, as shown in dotted lines in Fig. 7. A plurality of pairs of laminations 53, 55 are positioned between the laminations 56, 58 and 57, 59, respectively, forming spacers therefor.

The rotor 70 may be formed of two identical laminations secured to a hub 72, the latter being non-rotatably secured to a shaft 74. The rotor 64 of the induction motor is pressed over a pinion 76 which is freely rotatable upon the shaft 74. The shaft 74 is rotatably mounted in suitable bearings formed in plates 78, 80 secured to frame plate 24 and bearing plates 82, 84 secured to frame plate 22. These bearing plates are made of a phenolic condensation product or similar material, and will hereinafter be described in greater detail.

The gear trains and spring motor

As best shown in Figs. 9 and 10, the pinion 76 is in mesh with a gear 86, which is secured on a sleeve 87 and freely rotatable upon a shaft 88, and has a pinion 90 secured thereto. The pinion 90 meshes with a gear 92 secured to a sleeve 94, which is rotatable upon a shaft 96. The opposite end of the sleeve 94 has a pinion 98 secured thereto meshing with a gear 100 which is rigidly secured to a shaft 102. The gear 100 carries a pinion 104 which meshes with a gear 106, the latter being freely rotatable upon a shaft 108 and 75

carrying a pinion 110. The pinion 110 meshes with a gear 112 formed on the spring drum 114, the latter being mounted for free rotation upon the spring shaft 116. A spiral clock spring 118 has its outer end secured to the spring drum and its inner end secured to the shaft 116.

The above described gear train thus is adapted to transmit power from the induction rotor 64 to the spring drum to wind the same, or rather, in normal operation, to maintain the same wound. A similar gear train is utilized for transmitting the power of the spring to the synchronous brake. This gear train comprises gear 120 secured to the shaft 116 and meshing with pinion 122 secured to shaft 108. The pinion 122 is rigid with a gear 124, the latter meshing with the pinion 126, freely rotatable on the shaft 102. A gear 128 is fixed to the pinion 126 and meshes with a pinion 130, the latter being fixed to shaft 96. The opposite end of the shaft 96 has a gear 132 secured thereto, the latter meshing with a pinion 134 secured to the shaft 88. A gear 136, rigid with the pinion 134, drives a pinion 138 secured to the shaft 74. As previously stated, the rotor 70 is rigidly secured to the shaft 74. The last described gear train is thus adapted to transmit the driving energy of the spring 118 to the rotor assembly of the synchronous brake. The rotor 64 of the induction motor and the rotor 70 of the synchronous brake rotate in the same direction, and it will be noted that corresponding gears of the two trains are in each instance mounted on the same axis, and since the gear ratios are identical, each gear which is rotatable on a shaft will, during normal operation of the clock, rotate in the same direction and at the same speed as the shaft upon which it is mounted. Thus there will be extremely little wear in the bearings of the gears and pinions which are rotatably mounted upon the shafts, the only bearings continuously subjected to wear being those of the rotatable shafts. By providing the gearing in this manner, I have in effect eliminated one-half of the bearings which would otherwise be necessary. Due to the improved bearings which I have provided for the ends of the shafts, the wear upon bearings has been greatly reduced and the clock mechanism made more durable. It will be understood that the only time when the gears which are rotatably mounted upon a shaft rotate relative to the shaft is during intervals of current interruption when the train of gearing between the rotor 64 of the induction motor and the spring drum 114 is stationary, and following an interruption when the spring is rewound.

The gearing ratio is such that the shaft 108 will rotate at one revolution per minute, and the second hand 44 may therefore be secured to the end of this shaft. The shaft 108 has a pinion 140 secured thereto which meshes with a gear 142 rotatably mounted upon a shaft 144. The gear 142 is rigidly connected to a pinion 146 which meshes with a gear 148 rotatably mounted upon the shaft 108. The latter gear is rigidly connected to a sleeve 150 surrounding the shaft 108 and at its end carrying the minute hand 42. The gear 148 is frictionally rotated with the shaft 108 by a spider spring 149 compressed between the pinion 140 and the side of the gear 148. The pinion 152 secured to the gear 148 meshes with a gear 154 secured to the shaft 144. The gear 154 has a pinion 156 secured thereto and projecting outwardly through the frame 20, the pinion 156 meshing with a gear 158 secured to the

hour hand sleeve 160. It will thus appear that the time indication of the clock is taken from the rotation of the shaft 108.

The hands of the clock may be set in the usual manner by rotating a thumb nut 162 secured to a stem 164, the latter being rotatably mounted in the frame plates of the clock and having a pinion 166 secured thereto and meshing with the pinion 154.

A knurled starting thumb piece 168 is secured to a shaft 170, the latter being mounted for rotation and axial movement in the frame plates 22 and 24 and carrying a pinion 172, adapted to mesh with gear 132 when the thumb piece 168 is pushed inwardly. A spring 174 normally holds the pinion 172 disengaged from the gear 132. This thumb piece is used only in starting the clock, as will hereinafter appear.

The drum 114 of the spring motor has a ratchet wheel 176 secured thereto or formed integrally therewith. A pawl 178, freely pivoted at 180 to the outer end of an arm 182, rests by gravity upon the drum 114 and has a tooth 184 adapted to engage the teeth of the ratchet wheel 176. The arm 182 is rigidly secured to a sleeve 186 which is capable of only limited rocking movement, and thus prevents clockwise movement of the ratchet wheel 176 except through a small angle, as indicated in Fig. 6 by the full and dotted line positions of the pawl 178. A stop pin 188 limits counter-clockwise movement of the sleeve 186 by arresting the movement of the arm 182.

The centrifugal brake mechanism

A hub 190 (Figs. 5 and 9) is rotatably mounted on the shaft 74 and has secured thereto a bar 192, the outer ends of which have inwardly and sidewardly bent flanges 194. Leaf springs 196 are riveted to the flanges 194 and at their ends carry weights comprising two portions 198 and 200, secured together and to the ends of the springs 196 by screws 202. A head 204 is rigidly secured to the end of the shaft 74 and has a diametrical slot 206 formed therein. A wire spring 208 is bowed to have its ends projecting through openings 210 formed in the bar 192 and its mid portion engaged in the slot 206. This spring has the double function of resiliently connecting the bar 192 for rotation with the shaft 74 and drawing the hub 190 against the end of the head 204 so that a certain amount of friction will be present between the head and the hub 190. The centrifugal weights are partially enclosed in a circular race 212, which is substantially Z-shaped in cross section and is pivoted to the frame plate 24 by a bolt or rivet 214. The race has an inwardly projecting lug 216 which extends through an opening 218 formed in the frame plate 24. A pair of blocks 220 are threaded to receive adjusting screws 222 and 224 to limit the extent of pivotal movement of the race 212. The race 212 is normally held in its lowermost position with the ear 216 resting upon the adjusting screw 224 by the force of gravity, but is adapted to be raised upon an interruption of the supply of current by means of an arm 226, which is secured to the sleeve 186. It will be recalled that the sleeve 186 is rocked clockwise (Figs. 3 and 11) by the pawl 178 and arm 182 when the current is interrupted, and the spring drum permitted to rotate clockwise.

The self-oiling bearings

As previously described, the various shafts are mounted for rotation in bearings composed of a

pair of plates made of a phenolic condensation product or similar material. In Fig. 8, one of the inner bearing plates 80 is shown as having a plurality of perforations 230 formed therein. These perforations are in addition to the holes formed for the bearings and are adapted to be filled with oil when the clock is being assembled. The plate 80 is covered with a plate 78 of the same material as plate 80. The plates 78 and 80 are secured to the frame plate 24 by means of suitably spaced rivets 232. There is of course a minute crevice between the two plates 78, 80, which permits gradual seepage of the oil from the perforations 230 to the bearings. In this manner, the shaft bearings are amply supplied with lubricant for a large number of years. While this type of bearing is extremely useful in connection with the present invention, it may of course be used with other kinds of clocks and various other mechanisms.

Operation

Assuming that the plug 54 has been connected to a source of alternating current of regulated frequency, the operation of the clock is as follows: As soon as a connection with the source is made, the rotor 64 of the induction motor, due to the rotating field formed by the shaded poles of the laminations 56, 58, commences rotating, and through the gear train between it and the spring drum 114 commences winding up the spring 118. The rotor 70 of the synchronous brake will be held stationary by the magnetic flux since its field is not rotating, but on the contrary its pole pieces have teeth which register with and attract the teeth of the rotor. The spring, even when fully wound up, is not sufficiently strong to move the rotor 70 of the synchronous brake out of its magnetically "locked" position. Thus, unless the synchronous brake is moved from its locked position, the induction rotor 64 would continue to operate until the spring 118 was fully wound up.

As soon as the user has connected the plug 54 in a suitable socket, he is instructed to push in and rotate the thumb piece 168 clockwise. When the thumb piece is pushed in, the pinion 172 connected to its stem 170 engages the gear 132 so that when the thumb piece is manually twirled, the shaft 74 and all parts connected therewith are rotated, the rotor 70 of the synchronous brake being forcibly moved out of its magnetically locked position. As soon as the rotor rotates at any appreciable speed, the poles of the synchronous brake do not exert any great magnetic attraction until the rotor attains synchronous speed. Manual rotation of the shaft 74 at much greater than synchronous speed is prevented by the frictional engagement of the weights of the centrifugal mechanism against the inside wall of the raceway 212. As the rotor 70 approaches synchronous speed, its magnetic field exerts a relatively powerful torque upon it, tending to prevent deviation from this synchronous speed. Unless some means are provided to dissipate energy at the instant that the rotor 70 falls into synchronism, there is a probability that the rotor will not "fall into step." The theory and principles of the operation of the rotor with reference to its coming into synchronism are substantially the same as those of a similar rotor of a synchronous motor, such, for example, as is shown and described in Patent No. 1,719,805, granted to me on July 2, 1929. In the present construction, the bar 192, together with the

weights 200, forms the inertia member and corresponds to the inertia washer disclosed in said patent. It will be noted that the bar 192 is frictionally connected to rotate with the shaft because of the friction between its hub 190 and the head 204. The friction between these parts should be considerable, but must be small enough to permit of relative motion when the rotor falls into step. The spring 208 has sufficient play and is sufficiently pliable that it does not materially interfere with the utility of the bar 192 and the parts carried thereby as an inertia means to insure falling into step of the rotor 70 of the synchronous brake, but of course causes the bar 192 and associated parts to rotate with the shaft 74 except for such minor relative rotation as is desirable to cause the rotor of the synchronous brake to fall in step and to prevent it from hunting.

Having brought the synchronous brake rotor 70 up to synchronous speed, it will continue to be driven by the spring 118 and will act as a nearly perfect governor to control the speed of unwinding of the spring in synchronism with the frequency of the alternating current supply. The rotor 64 constitutes a variable speed motor which is of the induction type. It is capable, however, of running at a speed several times the synchronous speed of the rotor 70, so that even though the rotor 70 is started substantially at the same time that the clock is connected to a source of alternating current, it will within a short time completely wind the spring 118, or at least will wind the spring to an extent where the torque from the spring tending to rotate the rotor 64 in a reverse direction is exactly equal to the torque developed by the rotor 64 when rotating at the same speed as the rotor 70. While the clock is operating in this manner, the pawl 178 will be in the position shown in dotted lines in Fig. 6, since the ratchet wheel 176 will be rotating counterclockwise. Thus the raceway 212 will be in its lower position with its lug 216 resting against the lower adjusting screw 224. In this position the weights do not hit against the raceway when the shaft 74 is rotating at synchronous speed. The centrifugal mechanism thus has no effect upon the rotation of the shaft 74 except to act as an antihunting means.

Upon an interruption in the supply of the current to the clock, the rotor 64 will of course be incapable of exerting a torque, and the spring 118 will rotate it in the reverse direction. This reverse rotation will, however, be arrested within a very short time by the pawl 178, which will be moved from the dotted line to the full line position (Fig. 6), and during this movement pivot the arm 226 and raise the raceway 212 until its lug 216 abuts against the upper adjusting screw 222. Thereafter, further reverse rotation of the induction rotor 64 is prevented. The rotor 70 of the synchronous brake continues rotation at substantially synchronous speed. There is, of course, a slight tendency for all the parts connected to the shaft 74 to rotate at an increased speed. This tendency is counteracted in a large measure by the inertia of all the rotating parts and by the frictional drag exerted as the induction rotor 64 rotates in the reverse direction. It has been found that during the interval that the pawl 178 moves from dotted to full line position (Fig. 6), the speed of rotation of the rotor 70 will remain at so close to synchronous speed that it will seldom slip even a single tooth. (This test may be made by observing the rotor under the

illumination of a neon glow lamp held adjacent the rotor of the synchronous brake and then disconnecting the supply of current to the clock.)

When the pawl 178 is moved to its full line position and the raceway 212 raised with its lug 216 against the adjusting screw 222, the lower portion of the raceway will be in position frictionally to engage the weights 200 should the speed of the shaft 74 exceed its normal synchronous speed. This centrifugal regulating mechanism has been found to be extremely accurate. During a period of half an hour's run, the cumulative error is found to be not more than a few seconds. Since interruptions in the supply of current to an electric clock are usually of comparatively short duration, the centrifugal mechanism can ordinarily cause an error of only a fraction of a second for such period, usually of less than a minute's duration.

Upon resumption of current supply to the clock, the induction rotor 64 will of course again commence rotation and again wind the spring 118. As it winds this spring it will permit the pawl 178 to resume its normal position (shown in dotted lines in Fig. 6), whereupon the raceway 212 will again drop to its lower position with its lug 216 resting on the lower adjusting screw 224. As soon as the supply of current is resumed, the rotor 70 of the synchronous brake will immediately fall into step and again act as the effective brake to control the speed of operation of the clock. It will be noted that the raceway 212 forms a partially enclosed chamber for the weights 200, thus decreasing the air friction on these parts.

Theory of operation

In order that the clock may operate as above described, certain fairly definite quantitative relationships must be present. As previously stated, the amount of friction between the hub 190 and head 204 plays an important role in accordance with the theory set forth in my prior Patent No. 1,719,805. In addition to this relationship, the induction motor must be capable of developing more than sufficient torque to rotate all of the normally rotating parts of the clock and to urge them continuously to run at greater than correct speed, the surplus of the power being absorbed by the synchronous brake.

To insure operation of the clock when the current is turned off (and hence no counter torque exerted by the braking rotor 70), the spring 118 must be capable of developing sufficient torque to overcome the friction in the gear train between the shaft 116 and the shaft 74, to overcome the friction in the auxiliary gear train driving the hands of the clock, and to overcome the friction exerted upon the shaft 74 and the centrifugal governing mechanism. The spring 118 must not, however, be capable of exerting sufficient torque to overcome the friction of the gear train between the shaft 116 and the shaft 74 and at the same time to move the rotor 70 out of its magnetically "locked" position.

Instead of moving the raceway 212 from one position to another when the current is turned off, the raceway could be adjusted and held firmly fixed in a position where the weights 200 would just miss striking against the raceway. In such a construction, the synchronous brake would maintain the speed during the period that current is being supplied, and as soon as the current was interrupted, the shaft 74 would slightly increase its speed of rotation until the

weights contacted with the wall of the raceway. This would result in a temporarily slightly increased speed during the interval of current interruption, but the increase could be made so slight that the cumulative error would ordinarily not be noted for an interruption of usual duration. With the omission of the means for changing the position of the raceway, the weights 200 might strike the raceway during normal operation and slightly interfere with correct operation should the frequency of the current supply temporarily greatly exceed its nominal frequency, and there might be a slight tendency for the weights 200, if the position of the raceway was not adjusted exactly correctly, occasionally to strike against the raceway, thus making the clock slightly noisy in operation. With the preferred construction previously described, this noise incidental to the striking of the weights 200 against the raceway occurs only during the periods of current interruption and thus serves a useful purpose in indicating that such interruption is taking place.

The pendulum speed governor

In Figs. 12 and 13, I have illustrated a modified mechanical speed governing means which may, if desired, be substituted for the centrifugal mechanism previously described, although the latter has several advantages not present in the pendulum control mechanism. In the construction illustrated, the rotor 70^a of the synchronous brake is rigidly secured to a shaft 74^a. A pinion 240 having a hub 242 is secured to the shaft 74^a and meshes with a gear 246, which is rotatably mounted upon a shaft 248. A crank disc 250 having a hub 252 is also rotatable upon the shaft 248 but is resiliently constrained to rotate with the gear 246 by a torsion spring 254, one end of which is secured to the gear 246 and the other end of which is anchored to the disc 250. The disc 250 has a crank pin 256 which is connected by a link 258 with a pin 260 at the end of an arm 262 formed integrally with a friction plate 264. The plate 264 is secured to the rod 266 of the pendulum by a bolt 270, the plate being pressed against a disc 272 of friction material by a spider-shaped spring 274. The degree of pressure exerted by the spring 274 may be readily adjusted by means of the thumb nut 278 threaded on the bolt 270. The pendulum rod is supported by flat spring 280 suspended from any suitable support 282, being secured to the support by a bolt 284. The lower end of the spring 280 is secured to the pendulum rod by a screw 286. The pendulum has the usual bob 288, the position of which may be adjusted by means of nut 290 and lock nut 292. A collar 289 is rigidly secured to the shaft 74^a and carries a pair of washers 291 which are mounted for free rotation upon the collar 289. These washers serve as a frictionally connected inertia means for aiding in causing the synchronous brake to fall into step, and for minimizing hunting, as fully set forth in my aforesaid patent. The rotor of the induction motor and the driving pinions have, for the sake of clearness, been omitted from Figs. 12 and 13.

It will be understood that the mechanism shown in Figs. 12 and 13 is incorporated in the previously described clock in lieu of the centrifugal governing mechanism. In normal operation of the clock with the current on, the rotor 70^a will of course act as a synchronous brake and control the speed of the clock. During such nor-

mal operation, the shaft 74^a will, through pinion 240, gear 246, crank disc 250, and link 258, oscillate the pendulum. It will normally be attempted to adjust the length of the pendulum so that it will swing in exact synchronism with the alternating current supply. Such adjustment is, however, impossible due mainly to the slight variations in the frequency of the supply, and the pendulum is therefore adjusted so that it will tend to oscillate at a frequency slightly less than the frequency at which it is actually oscillated by the crank rod 258 when the synchronous brake is operating to retard the speed of rotation of the shaft 74^a. The degree of friction between the discs 264 and 272 is sufficiently great that there will be no relative movement between the plate 264 and the pendulum rod 266 during such normal operation. The pendulum is, however, continuously "crowded" by its driving means.

When an interruption occurs in the supply of current, the speed of rotation of the shaft 74^a will be accurately controlled by the pendulum. When the braking effect of the synchronous rotor brake 70^a is removed upon a current interruption, the full force of the main driving spring will be effective to oscillate the pendulum and would, unless deterrent means were provided, tend to increase the amplitude of oscillation of the pendulum far beyond that permitted by the throw of the crank pin 256. The frictional connection between the plate 264 and disc 272 is therefore provided so that, as the pendulum tends to increase the amplitude of its oscillation beyond that permitted by the crank pin 256 and connecting link 258, there may be relative movement between the plate 264 and the disc. This relative movement between these parts will result in dissipation of the excess energy provided by the main driving spring and thus permit the pendulum to oscillate only at its normal amplitude and to maintain its time-keeping characteristics. If the frictional connection were not provided the parts of the pendulum driving mechanism would be subjected to excessive stresses and the period of oscillation of the pendulum would be materially shortened.

The spring 254 forms a resilient driving connection which tends to take up minor irregularities in the relative speeds of the pendulum 50 and its driving gear 246, and acts as a means to insure continuous harmonious oscillation of the pendulum even though the gear 246 is not rotating in exact synchronism with the pen-

Balance wheel escapement mechanism

As a second alternative construction, I may utilize a balance wheel escapement mechanism to control the speed of rotation of the rotor shaft during intervals of current interruption. In Figs. 14 and 15, I have illustrated one form of a suitable mechanism of this type.

In this construction the rotor 70^b of the synchronous brake is rigidly secured to a shaft 74^b, to which is also secured a pinion 294, the pinion meshing with a gear 296 secured to a shaft 298. Inertia washers 299 are mounted upon the shaft 74^b in the same manner as the inertia washers 291, previously described. A pinion 300 is freely rotatable upon the shaft 298 but is constrained to rotate with the shaft by a torsion spring 302, one end of which is secured to the gear 296 and the other end of which is staked to the pinion 300. The pinion 300 is in mesh with a gear 304 which is rigidly secured to an escapement

wheel 306 suitably mounted on a shaft 308. The pallets of anchor 310, secured to a pivotally mounted shaft 312, are engageable with the teeth of the escapement wheel 306 and are operable to oscillate a balance wheel 314. The balance wheel is preferably mounted in the usual manner, having a hair spring 316, one end of which is anchored at 318 and the other end of which is secured to the balance wheel staff 320. Suitable hair spring tension adjusting means (not shown) may of course be provided.

In order to be operative for the desired purpose in combination with the previously described clock, the balance wheel escapement mechanism must have the property of increasing its speed of oscillation with increased driving power. This may be accomplished in various ways, the one illustrated being the provision of a stop pin 322 on the balance wheel which is adapted to strike against a fixed stop 324 at both ends of its travel. Thus, if the balance wheel tends to oscillate at a frequency less than that required to permit rotation of the shaft 14^b at its synchronous speed, the spring 302 will have its tension increased and a greater force exerted upon the escapement pallets, and thus tend to oscillate the balance wheel through an ever increasing arc. When thus endeavoring to oscillate through an angle approaching 360°, the pin 322 will at both ends of its stroke strike against the fixed stop 324 and the balance wheel will thus complete its oscillatory cycle in a shorter time.

In normal operation of the clock with the current on, the rotor 70^b of the synchronous brake will of course govern the speed of operation of the clock, and during such normal operation the balance wheel escapement mechanism will merely act idly. When, however, the supply of current to the synchronous brake is interrupted, the balance wheel escapement mechanism will become effective to control the speed of rotation of the shaft 14^b. This balance wheel escapement mechanism does not have all the advantages which are present in the preferred construction incorporating the centrifugal speed governing mechanism, but is a practical construction which may be found desirable under certain circumstances. It has the slight disadvantage of being noisy during normal operation of the clock.

Having described my invention, what I claim and desire to secure by Letters Patent is:

1. A time-keeping device having a motor, and means to control the speed of operation of the motor; said means comprising an electric synchronous brake supplied with alternating current of regulated frequency, a member rotated by said motor, an element resiliently secured to said member and movable outwardly from the axis of rotation thereof, a stop normally stationary with respect to said member, and means for positioning said stop in the path of outward movement of said element thereby to impede rotation of said member at greater than a predetermined speed, said last named means being energized upon an interruption in the supply of current to said synchronous brake to move to operative position.

2. In a time-keeping device, the combination of an induction motor, a synchronous brake, a spring, a frame supporting said motor, brake and spring, and a pair of gear trains one connecting said brake and spring and the other connecting said motor and said spring, said

5 gear trains comprising a plurality of shafts rotatably mounted in said frame, each shaft having a gear and pinion fixed thereto and a gear and pinion rotatable thereon, the fixed and the rotatable gears and pinions normally rotating in the same direction.

10 3. A clock mechanism having a frame, a spring motor, and a pair of independent gear trains, said gear trains comprising a plurality of rigidly joined gear and pinion assemblies, a plurality of shafts rotatably mounted in said frame, each of said shafts carrying a pair of gear and pinion assemblies, one of the assemblies being rigidly secured to the shaft and the other assembly 15 being rotatable relative to the shaft, and both of said pairs of assemblies normally rotating in the same direction at approximately the same speed, one of said pairs of gear trains being connected to said spring motor to supply energy thereto and the other to withdraw energy therefrom.

20 4. In a device having a timing function, the combination of mechanism for utilizing the timing function, means to drive said mechanism, an alternating current source, brake means responsive to the alternations of the current from said source for limiting the speed of operation of said mechanism, centrifugal speed governing means connected to said mechanism, and means 25 under the control of said driving means to render said centrifugal means operative to control the speed of operation of said mechanism when the supply of current from said source is interrupted.

25 5. In a time-keeping device, the combination of a motor, a synchronous electric brake and a mechanical speed governor both connected to be driven continuously by said motor and adapted to govern the speed of operation thereof, said 30 governor comprising an oscillatable pendulum, and a frictional yieldable driving connection between said motor and said pendulum.

35 6. In a time-keeping device, the combination of a shaft, a synchronous electric brake rigidly secured to said shaft, a crank, a yieldable resilient driving connection between said shaft and said crank, an oscillatable pendulum, and a frictional driving connection between said crank and said pendulum.

40 50 7. In a time-keeping device, the combination of an energy storing motor, a synchronous electric brake connected to a source of alternating current, driving gearing connecting said motor with said brake, an induction motor, driving gearing 45 connecting said induction motor and said energy storing motor whereby energy may be transferred from the former to the latter, a pendulum, and means for driving said pendulum from energy derived from said energy storing motor, said means including a yieldable spring and a frictional driving connection.

45 65 8. In a time-keeping device, the combination of an energy storing motor, a synchronous electric brake, means for connecting said synchronous electric brake to a source of alternating current, an induction motor for supplying energy to said energy storing motor, means for preventing said energy storing motor from driving said induction motor in a reverse direction upon interruption 50 of current to the latter, a mechanical speed governing mechanism driven by said energy storing motor in synchronism with said brake, and control means for regulating said mechanism upon operation of said second-named means.

70 9. In combination, a spring motor, a variable

speed electric motor, a mechanism to be driven, a gear train connecting said spring motor and said mechanism, and a second gear train connecting said electric motor and said spring motor, one of said gear trains having a gear secured to a rotatable shaft and the other of said trains having a gear mounted for rotation on said shaft, said gears being arranged normally to rotate in the same direction at substantially the same speed.

10. In combination, a spring motor, a variable speed electric motor, a mechanism to be driven, a gear train connecting said spring motor and said mechanism, and a second gear train connecting said electric motor and said spring motor, said gear trains comprising a plurality of rotatably mounted shafts each having a gear and pinion fixed thereto and a gear and pinion rotatable thereon, the latter gear and pinion normally rotating in the same direction and at the same speed as the shaft.

11. In a clock, the combination of an escapement mechanism comprising an escapement wheel, a pallet fork, a balance wheel and a hair spring, a synchronous electric motor, means actuated by said motor for controlling the oscillations of said balance wheel, and resilient means functioning automatically under certain abnor-

mal conditions of operation of said balance wheel to increase the frequency of said balance wheel whenever the amplitude thereof is increased to a predetermined degree.

5 12. In a clock, the combination of an escapement mechanism comprising a balance wheel, said wheel having a projection thereon, a synchronous electric motor, means actuated by said motor for controlling the oscillations of said balance wheel,

10 and resilient means adapted to be engaged by said projection on the balance wheel when the amplitude of motion of said wheel is maintained beyond a predetermined degree by said oscillation controlling means.

15 13. In a time keeping device, the combination of a motor, a synchronous electric brake and an adjustable mechanical speed governor both connected to be driven continuously by said motor, the normal adjustment of said governor permitting rotation of said brake at greater than its synchronous speed, and means actuated from said motor and operable upon an interruption of the current supply to said brake to change the adjustment of said governor, whereby said governor will become effective to prevent the speed of said brake from exceeding the normal synchronous speed of the latter.

LAURENS HAMMOND.
